DISPLAY CARD HOLDER

Miriam Alice Obrist, Brooklyn, N. Y.

Application May 1, 1941, Serial No. 391,394

2 Claims. (Cl. 40—16)

This invention relates to display card holders, and it consists in the constructions, arrangements and combinations herein described and claimed.

It is a cardinal object of the invention to provide a support means for effectively displaying price, name or similar cards, which may be readily molded as a unitary device from transparent plastic material.

It is a particular object of the invention to provide card holding devices of a portable character in which the card is displayed at such an angle that the inscription on the card will be readily discernible whether viewed from a point directly in front or at an angle thereto.

It is a further object of the invention to provide a card holding or support device in which the card may be readily inserted or removed from the device, and in certain forms of the support, the card will be retained in a manner to prevent accumulation of foreign matter, such as dust, upon the face of the card.

It is a still further object of the device to provide the holder in such manner that magnification of the inscription on the card is attained, making it possible to read the card from considerable distances.

Additional objects, advantages and features of invention will be apparent from the following description considered in conjunction with the accompanying drawing, wherein

Figure 1 is a perspective view of one of the card holders,

Figure 2 is a front view thereof.

Figure 3 is a vertical section of the device.

Figure 4 is a cross section on the line 4—4 of Figure 3.

Figure 5 is a vertical sectional view of a modified form of the holder.

Figure 6 is a cross section on the line 6—6 of Figure 5.

Figure 7 is a front view of a further form of the device.

Figure 8 is a vertical section thereof.

Figure 9 is a front view of a modified form shown in Figure 7.

Figure 10 is a vertical section therethrough.

From a consideration of the constructions presented it will be noted that all forms of the holder embody parallel opposed slots or kerfs for removable reception of a display card, the card being supported in a manner to be clearly discernible through a transparent front face.

The specific construction will now be dealt with, attention being first invited to Figures 1 to 4,

respectively. The form here shown is of a magnifying type and consists of a body member 10 of transparent material molded or otherwise formed to define a semi-spherical lens 11. Front 5 and rear legs or support members 12 and 13, are integrally formed with the body 10, the front legs 12 being approximately one-half the length of the rear legs 13, so that the medial axis of the lens will be at an angle to the vertical axis of the holder. Preferably the rear legs 13 are formed with an intermediate concave portion 14 and each of the legs 12 and 13 are formed with planiform bases complementary to a supporting surface to afford suitable support for the holder.

15 Upon each of the leg members 12 and 13 spaced a suitable distance below the base of the semi-spherical lens 11, a kerf or slot 15 is formed, in opposed parallel relation, the kerfs being of a width readily receiving a display card or marker 20 16 therebetween, the card being of such width as to be readily insertable longitudinally along the kerfs. In the figures just described, the kerfs are spaced downwardly from the inner face 17 of the lens 11 in order to obtain a greater magnification 25 of the marker, such as might be required in display of price markers in store windows, place markers at dinner parties and other situations where it would be desirable to magnify a legend of a supported card.

30 In Figures 5 and 6, a modified form is shown, and consists of a semi-spherical lens 11', supporting legs representing the front and rear legs respectively, the front legs 12' being of much shorter length than the rear legs 13' and therefore presenting the lens 11' at a greater angle than in the first form. Also, it should be noted that the kerfs 15' are formed immediately below the lower face of the lens 11' so that a marker or price card 16' will fit flush or snugly thereagainst, as shown. In the forms thus far described, the lens is semi-spherical as viewed in front elevation, the marker card being insertable transversely, and accordingly, the marker is formed with arcuate ends and of a length slightly less than the diameter of the lens so as to fit well within the boundary of the lens.

45 Obviously, the holder may be made in other shapes and sizes and in Figures 7 to 10 the holder or support 10 is shown as comprising an elongated structure especially suitable for support of markers of greater lengths. The structures here shown are very similar to the structures of Figures 5 and 6, but it will be noted that the rear leg 13'' is arranged in a vertical plane with respect to the medial axis of the lens.

From the foregoing description it will be apparent that I have provided a marker support which may be cheaply produced, of attractive forms and which will tend to attract attention to articles which might otherwise be unobserved.

I have described the support as a price marker, particularly, but obviously, many uses may be found for the device, such as combined paper weight and name plates, or the marker may be replaced by a photograph, and in the latter case, the photograph would be retained clean from foreign matter and dust, when such forms as shown in Figures 6 to 10 are employed.

While I have specifically shown and described the various forms of my invention, this is by way of illustration only, and I consider as my own all such modifications in structures as fairly fall within the scope of the appended claims.

I claim:

1. As a new article of manufacture, a display card holder comprising a transparent body hav-

ing a magnifying front lens and a supporting base consisting of widely spaced front and rear legs adapted to be positioned upon a flat support surface, the front legs being shorter than the rear legs whereby to position the lens at an angle to the vertical axis of the body, said body having means beneath the lens for support of a display card.

2. As a new article of manufacture, a display card holder comprising a one-piece transparent body having a magnifying front lens and a support base consisting of widely spaced front and rear legs adapted to be positioned upon a flat support surface, the front legs being shorter than the rear legs whereby to position the lens at an angle to the vertical axis of the body, said body having a pair of opposed parallel slots beneath the lens, and a display card member frictionally engaged between the slots.

MIRIAM ALICE OBRIST.
